UNITED STATES PATENT OFFICE.

EARL G. WATROUS, OF SMITH'S MILLS, NEW YORK.

AUTOMATIC GRAIN-BINDER.

SPECIFICATION forming part of Letters Patent No. 392,650, dated November 13, 1888.

Application filed March 20, 1885. Serial No. 159,506. (No model.)

To all whom it may concern:

Be it known that I, EARL G. WATROUS, of Smith's Mills, in the town of Hanover, county of Chautauqua, and State of New York, have 5 invented certain Improvements in Automatic Grain-Binders, of which the following description, in connection with the accompanying two sheets of drawings, constitutes a specification.

10 This invention relates to novel devices for gathering, compacting, and confining the cut grain of which the sheaf is composed preparatory to and during the operation of binding the same, to devices used in connection 15 therewith for discharging the bound sheaf from the binding-table, and also to a new combination of the operative parts of a grain-binder, whereby the tension may be wholly or partially applied to or withdrawn from the binding-twine as the exigencies of the binding process may require.

As my apparatus is susceptible of being applied or adapted to a great variety of grain-binders, especially to different styles of knot 25 or band tyers, I have not shown in the drawings any knot or band tying mechanism, and only so much of a binding-table as is necessary to elucidate my invention.

Figure 1 of the drawings shows the relative 30 position of the several members of my apparatus at the finish of the stroke or throw which discharges the bound sheaf, in which position the machine remains at rest pending the accumulation of straw for the next sheaf. Fig. 2 shows the position of the same parts at 35 the moment of tying the knot or of securing the sheaf-band. Fig. 3 shows an adaptation of the needle-arm to co-operate with the device provided to regulate the degree of tension applied to the binding-twine.

My apparatus as here shown is adapted to be used in connection with any variety of knotter or band-tyer located beneath the binding-table A. It consists of a needle-arm, E, 45 mounted on shaft D, which has a rotary reciprocating motion imparted to it from some part of the machinery of the binder, so that it can oscillate from the position seen in Fig. 1 around to the position shown in Fig. 2, and 50 back again. Needle-arm E has a projection,

L, to the extremity of which the link G is pivoted at v. This link connects with the discharging-arm M at u. The discharging-arm M is substantially of the shape shown, and is hung from the top of a bracket-arm, C, which 55 is an upward projection from standard B. At the point n on the discharging-arm the compressing-arm R is attached. This has a slotted prolongation, K, and through the slot R' the set-screw N passes and screws into the dis- 60 charging-arm. The slot R' and set-screw N are provided as a means of adjusting the gap of separation between arm R and the needle-arm E when they are in the act of compressing a bundle. To the compressing-arm R is 65 affixed the compressing-spring H. This spring is so constructed and attached that normally it stands about as in Fig. 1—that is, with its free end advanced a little ahead of the lower end of arm R, so as to engage with the ac- 70 cumulated straw a little in advance of the arm R. This, among other things, is to prevent the paying out of more binding-twine than will be taken up by the needle-arm in the act of binding.

The lower end of the discharging-limb M is bent back, as at O, as a provision for hanging thereto the foot J. This foot is pivoted to the discharging-arm at x, and its position is controlled and regulated by a spring, s, in connection with the stop lug or pin e. This construction permits foot J to be forced back into position shown in dotted lines in Fig. 2 as arm m sweeps back over the straw accumulated to form the next sheaf.

The knotting apparatus is located beneath table A, directly under sheaf S, in Fig. 2.

The oscillating motion of the needle-arm E is imparted through shaft D, which is provided at the end opposite the one in view with a crank-arm, which is connected by a pitman or otherwise with some driver on the binder.

I have shown in connection with the needle-arm in Figs. 1 and 3 a tension device, or "twine-brake," as it may more appropriately be called, 95 through which the cord passes from the twine-ball to the needle-arm, the action of which is controlled as to its time of operation by the motion of the needle-arm or of some other part of the binding machinery which has motion 100

synchronous with that of the needle-arm. It consists of a pair of jaws, *a* and *h*, connected by a bolt, *f*, which carries spring *b*, as shown, the force of which is normally exerted to keep 5 the jaws closed. The twine runs between jaws *a* and *h*, the outward lips of which are everted, so that the beveled edge *U* of arm *E* may easily enter between them and force them apart when the needle-arm makes its back-throw, 10 and thus relieves the tension on the twine.

The machine operates as follows: The twine is carried from the twine-ball through the twine-brake, thence through the various guides and eyes of the needle-arm to the knot- 15 ter at *W*, leaving the parts in position, as in Fig. 1, the jaws of the twine-brake being open, so that the twine may pay out freely as it is crowded back by the impact of the inflowing current of grain. The cut crop is carried up 20 in the direction of the arrows and forced under and against twine *g* until a sufficient amount is accumulated for a sheaf. Then at the proper moment the binder is started. The instant the needle-arm commences its descent 25 wedge *U* moves out from between jaws *a* and *h* of the twine-brake, thus permitting spring *b* to act to close them and bind the binding-twine between them. The degree of pinch or tension thus brought to act on the twine is 30 regulated by the regulating-nut *k*, which acts to compress or elongate the helical spring *b*. The amount of such tension, however, is sufficient, as arm *E* descends, carrying the twine around the sheaf in the usual way, to firmly 35 compact the straw inclosed within its embrace and make a tight, firm, and compact sheaf.

It is not material whereabout between the needle-arm and the twine-supply the twine-brake is located, provided the time of its action and intervals between its intermittent operations are synchronous with the movements of the needle-arm. The improved results attending upon the foregoing-described use of 45 the twine-brake are these: When the binder is at rest and the operation of gathering and compacting material for a new bundle is going on, which operation consists of forcing the cut straw against the binding-cord until a sufficiency for a bundle is accumulated, the twine yielding and gradually paying out during such process, it is obvious that the more tension there is put on the twine the more power will be used to overcome such tension, in order 55 to force the twine back to admit the straw, and this expenditure of power in this way is great and materially adds to the hard working of the machine, and such tension so maintained is wholly or mainly unnecessary and 60 harmful, inasmuch as with some machines it compacts the straw into a V-shaped mass, and when the needle-arm carries the cord around the bundle it folds or laps the thin edge of the mass around upon itself, and often leaves a 65 lank or hollow space in the bundle under the knot. When all or nearly all obstruction to the free running of the cord through its guide-

ways, eyes, &c., is taken off, this does not occur, and the straw is banked up in front of the twine in a symmetrically homogeneous 70 mass, which the encircling cord uniformly contracts and compacts.

To revert to the action of the needle and compressing arms, it may be stated that after the material of the bundle has been gathered 75 and compacted, as before stated, and the binding mechanism started, as the needle-arm *E* descends, by means of connection *G*, the discharging and compressing arms are dragged down and advanced to meet and co-operate 80 with arm *E*. In this movement the compressing-spring *H* acts by first engaging the straw and gradually yielding to the increasing pressure until arm *R* comes fully into position to accomplish its office in compressing the 85 bundle. If the spring *H* were not provided and arranged so to operate, it would result that when arm *R* did finally engage the straw and compress the same such compression, coming on so late in the process, would produce more 90 slack in the band than arm *E* and the knotting devices could take care of. Meanwhile discharging-arm *M* has swept across the sheaf, dragging the discharging-foot *J* over the bundle, as seen in Fig. 2, and has assumed the position shown in that figure. While the several parts are in this position the knot is tied and the cord severed. Then, by a reversed movement of shaft *D*, arm *E* recedes, and, concurrently, arm *M* and foot *J* advance. Foot *J* 100 is thus promptly and energetically impelled against sheaf *S*, with the result of sweeping it free and clear of the binding-table, disengaging it from the current of inflowing grain, and delivering it to a bundle-carrier or onto the 105 ground, as may be arranged.

To graduate the size of the bundle, the set-screw *N* may be loosened and arm *R* swung in or out, to suit the object sought, when it can be tightened up.

A marked advantage accruing from this construction is the complete and effectual severance of the bound sheaf from the current of inflowing grain, a separation of from two to two and a half feet being secured.

Another advantage results from the fact that the binding and compressing arms and the compressing-springs are all hung upon or are attached to the same limb or member of the binder-frame, whereby it is possible to make 120 such frame materially lighter than would otherwise be practicable. As one part works against the other, the opposing strains find common abutments of resistance at *t* and *D*.

The pitman-connection between the needle and compressing or discharging arms possesses advantages over a segmental gear-connection, in this, that either or both of the pitman-connections *u* and *v* may be made adjustable, and also the length of the pitman, so that the character of the sweep or stroke of the discharging and compressing arms may be considerably modified.

It will be observed that by reason of the

aforesaid pitman-connection a special advantage accrues in the avoidance of any sudden shock or blow to the sheaf at the moment of starting it from the table. By reference to Fig. 2 it will be seen that when the discharging movement is initiated pivot *v* moves in a direction almost at right angles to the line of motion of pivot *u*, thus starting the bundle very gently, its momentum gradually increasing until pivot *v* sweeps up around into position, where *D*, *v*, and *u* form a right angle, at which point its greatest force is exerted. By this time the sheaf is swept clear of the binding-table, either into a repository or carrier, or else into the field. This characteristic of the delivery-stroke cannot be obtained when the binding or needle arm and the discharging-arm are geared together, as when so connected they approach and recede with uniform momentum and force.

The arrangement of devices shown in Fig. 3 is made with reference to a needle-arm which swings from a position beneath the binding-table, the twine-brake being attached to some convenient part of the frame of the machine.

I therefore claim—

1. In a grain-binder, the combination of an oscillating needle or binding arm pivoted above the binding-table, an oscillating discharging-arm pivoted above the axis of the needle-arm, a compressing-arm attached to the discharging-arm, and a pitman connecting said needle and discharging arms, substantially as and for the purposes set forth.

2. In a grain-binder, the combination of an oscillating needle or binding arm pivoted above the binding-table, an oscillating discharging-arm pivoted above the axis of the needle-arm and connected thereto by a pitman, and a spring-controlled discharging-foot pivoted to the lower end of said discharging-arm, substantially as and for the purposes set forth.

3. In a grain-binder, the combination of an oscillating needle or binding arm pivoted above the binding-table, an oscillating discharging-arm pivoted above the axis of said needle-arm and connected thereto by a pit-

man, and a compressing-arm adjustably attached to said discharging-arm, substantially as and for the purposes set forth.

4. In a grain-binder, the combination of an oscillating needle or binding arm pivoted to a standard above the binding-table, an oscillating discharging-arm provided with a spring-controlled tripping-foot and pivoted to said standard above the axis of the needle-arm, a pitman adjustably connected to said arm, and a compressing-arm provided with a compressing spring and attached to said discharging-arm, substantially as and for the purposes set forth.

5. In a grain-binder, the combination, with the needle-arm, of a twine-brake located in the path and plane of the same, and consisting of the jaws *a* and *h*, the spring *b*, for compressing said jaws together, and an adjusting-nut, *k*, for regulating the tension of said spring, said needle-arm having a sharpened back adapted to enter the jaws *a* and *h* and force them apart as the needle-arm descends, for the purposes set forth, substantially as described.

6. The described discharging-arm provided with a discharging foot at its lower end and adapted to oscillate, substantially as shown, in combination with a compressing-arm equipped with a compressing-spring fastened near its upper end, said compressing-arm being adjustably attached to the upper end of said discharging-arm, substantially as described, and for the purpose set forth.

7. The combination of the discharging-arm *M*, spring-controlled foot *J* at the lower end thereof, compressing-arm *R*, pivoted to said discharging-arm, and spring *H*, slotted projection *K* at the upper end of said arm, and set-screw *N*, all combined for the purpose set forth.

In testimony whereof I have hereto affixed my name, at Smith's Mills, New York, this 14th day of February, A. D. 1885.

EARL G. WATROUS.

In presence of—

S. H. YORK,
G. E. WATROUS.
